UNITED STATES PATENT OFFICE.

EDWIN W. OLDHAM, OF CANTON, OHIO, ASSIGNOR TO THE HYGIENIC PRODUCTS COMPANY, OF CANTON, OHIO, A CORPORATION OF OHIO.

CLEANING-POWDER.

1,048,575.

Specification of Letters Patent. Patented Dec. 31, 1912.

No Drawing.

Application filed October 16, 1912. Serial No. 726,035.

To all whom it may concern:

Be it known that I, EDWIN W. OLDHAM, a citizen of the United States, residing at Canton, in the county of Stark and State of Ohio, have invented a certain new and useful Cleaning-Powder, of which the following is a specification.

The natural water supply used by many cities contains certain calcium salts either with or without iron salts, which gradually make an unsightly deposit in the porcelain water closet bowls and other similar vessels wherein the water is used; and the object of the present invention is to provide a dry powder which, when moistened or applied in the presence of water, will remove such deposits without injuring the vessel, and without any inconvenience or danger to the person applying the powder. The removal of such deposits by hydrochloric acid or other like liquids, is irritating because of the obnoxious vapors constantly given off from the solution, and also, when too much of the acid is inadvertently or ignorantly used, is damaging to the vessel by attacking the porcelain coating and is dangerous to the user by reason of its strength. These difficulties are avoided, and the object of the invention is attained, by mixing from two to four parts, preferably about three parts, of finely granulated or powdered sodium bisulfate with one part of kiln-dried sodium chlorid, likewise granulated, which forms a composition which may be readily and conveniently handled and which will accomplish the desired results, and will become active only in the presence of moisture or water.

In use, the bowl is first flushed so that the entire surface thereof to be cleaned is wet, and, after the flushing has ceased, a small

quantity of the powdered composition is poured or sprinkled into such water as there may remain in the bowl and also upon the inside surface of the bowl above the water line. The sodium bisulfate in conjunction with the sodium chlorid dissolves more lime than the bisulfate does when used alone.

The increased solubility resulting from the use of the sodium chlorid in combination with the sodium bisulfate, is no doubt caused by the fact that the presence of the sodium chlorid increases the solubility in water of the calcium sulfate which is formed by the action of the sodium bisulfate upon the calcium carbonate present in the coating. The deposit which remains in the bowl after the use and action of the cleaning powder is readily removed by again flushing the bowl, accompanied, if necessary, by a slight rubbing of the inner surface thereof.

It is not intended to limit the scope of the invention to the particular proportions of the ingredients set forth, nor to the use of the particular ingredients without the presence of other elements; for it will be understood that the exact proportions of the ingredients may be modified to correspond with varying conditions, and the present inventor believes himself to be the first one to include sodium bisulfate and sodium chlorid in a cleaning powder and to thereby accomplish the result set forth.

I claim:

A cleaning powder including a mixture of sodium bisulfate and sodium chlorid.

EDWIN W. OLDHAM.
